UNITED STATES PATENT OFFICE.

BENJAMIN SKIDMORE, JR., OF CHICAGO, ILLINOIS.

HYDROTURBINE VACUUM PUMPING APPARATUS.

Application filed April 28, 1924. Serial No. 709,452.

This invention relates to improvements in hydroturbine vacuum pumping apparatus and one of the objects of the invention is to provide an improved apparatus of this character by means of the use of which vapors, gases, air, and water of condensation may be drawn from a heating system and separated, the vapor, gases and air being discharged to the atmosphere and the separated water being delivered against a boiler or feed water heater pressure.

A further object is to provide an apparatus of this character having improved means whereby the pumping mechanism may be selectively controlled in its operation by the vacuum or the volume or height of water.

A further object of the present invention is to so combine and arrange the various parts whereby a compact structure will be provided and the cost of manufacture will be greatly reduced.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

Figure 1 is a side elevation of an apparatus of this character constructed in accordance with the principles of this invention.

Figure 2 is a vertical sectional view as taken on line 2—2, Figure 5.

Figure 3 is a vertical sectional view as taken on line 3—3, Figure 2.

Figure 4 is a vertical sectional view taken on line 4—4, Figure 2.

Figure 5 is a vertical sectional view taken on line 5—5, Figure 2.

Referring more particularly to the drawings the numeral 10 designates a tank or receiver which may be of any desired size and configuration and is open to the atmosphere as at 11.

Within the tank and preferably adjacent the bottom thereof but spaced thereabove is a casing 12 which is provided with an inlet opening 13 leading through the tank 10 from the outside thereof and out of communication with the tank. The casing 12 is also provided with an opening 14 leading through the tank 10 out of communication therewith and connected with the passage 14, prefer-

ably through the medium of a pipe 15, is a vacuum regulating valve 16 for controlling the vacuum in the casing 12.

The valve 16 may be of any desired and well known construction and is set for the predetermined degree of vacuum which is to be maintained in the pump, so that when the vacuum increases beyond the predetermined degree, the valve 16 will automatically operate to admit outside air into the pump casing to reduce the vacuum to the predetermined degree.

The vapors, water and air from the system are delivered into the casing of a rotor from the main line 17 and through the passage 13. Interposed between the main line or pipe 17 and the passage 13 is a strainer and a check valve designated generally by the reference numeral 18. The check valve and the strainer may be of any desired or suitable construction but is preferably of the construction shown and described in application, Serial Number 675,289, filed November 17, 1923. The outlet of the casing of the element 18 is connected with the inlet of the passage 13, while the inlet of the element 18 is preferably connected through the medium of a pipe 19 with the pipe 17.

A portion of the casing 12 is shaped to form a volute passage 20 having a discharge outlet 21 for delivering liquid, vapors and air into the tank 10.

A rotor designated generally by the reference numeral 22 in Figure 2, is arranged within the volute chamber 20 and this rotor may be of any desired and suitable construction. The rotor employed is preferably of the construction disclosed in United States Patent 1,390,890, issued September 13, 1921, suction being created in the passages 24 during the operation of the rotor and which passages 24 are in communication with the return line or pipe 17, through the medium of the chamber or casing 12, and the passage 13.

Liquid is supplied to the rotor from the tank 10 by means of a passage 25 which has communication with the rotor as at 26, the passage 25 being located within the tank 10 with the inlet 27 thereof terminating preferably at a point in proximity to the bottom of the tank.

As a means for providing a liquid seal for the end of the rotor 22, there may be provided a passage 28 in the wall of the casing which has communication with the

tank 10 and also with a chamber or passage 29 encompassing the end of the rotor. The rotor is operated preferably by means of an electric motor 30, the shaft of which is preferably connected through the medium of a suitable connection 31 with a shaft 32, the latter being preferably connected by one end to the rotor as at 33 and is journaled in suitable bearings 34 arranged within a casing 35.

- 10 Co-operating with the rotor 22 is a centrifugal pump 36 which operates within a casing 37. The casing 37 may be formed as a separate unit and connected to the wall of the tank 10 and the pump 36 is connected with the shaft 32 for operation therewith. Obviously a number of these centrifugal pump units may be connected with the shaft 32 when multi-staging is desired. The casing 37 has a discharge outlet 38 through which the liquid from the tank 10 may be discharged and this outlet 37 may be connected to any suitable point of use such as a boiler, hot well or a feed water heater into which the liquid is discharged 25 from the casing 37 against the pressure in the boiler, hot well or feed water heater.

Liquid from the tank 10 is supplied to the centrifugal pump 36 preferably through a chamber or passage 39, having an inlet opening 40, the latter having communication with the interior of the tank. The liquid level in the tank 10 may be controlled by the end 41 of the wall 42 of the chamber or passage 39, the end 41 of the wall being disposed at 35 a predetermined height at which it is desired to establish the liquid level in the tank. It will be manifest that with this construction when the liquid in the tank 10 rises above the end 41 of the wall 42, the excess 40 liquid will flow into the passage 39 through the opening 40 and will be supplied to the pump 36 through the opening 43. The pump 36 being rotated with the shaft 32 will pick up the liquid supplied thereto 45 through the passage 39 and will deliver the liquid through the discharge opening 38.

A supplemental closed tank 44 may be provided and has connection with the system, preferably to the return line 17, 50 through the medium of a pipe connection 45, and this tank 44 may be provided with an indicating gauge 46 for indicating the degree of vacuum existing in the tank 44. A vacuum controlled switch diagrammatically 55 illustrated at 47 has communication with the tank 44 through a connection 48, the switch 47 being of any ordinary and well known type. A magnetic switch diagrammatically illustrated at 49, and which may be of any 60 desired or suitable type, is provided for controlling the operation of the motor 30, one side of the switch 49 being connected with the motor through the conductors 50-51 and the other side of the switch 49 is connected with the source of supply of current

through the conductors 52-53, a neutral conductor 54 being also connected with the motor. A main line switch 55 is also provided for controlling the supply of current to the motor 30.

Leading from the main line conductor 54 is a branch conductor 56 which has connection with one side of the vacuum controlled switch 47, a cut out 57 being provided in the conductor 56 for cutting out the vacuum controlled switch 47 when desired. The other side of the switch 47 is connected through the medium of the conductor 58 with one side of the motor control switch 49, a conductor 59 being also provided and connecting opposite sides of the magnetic switch 49.

The vacuum controlled switch 47 is provided as a means for automatically controlling the operation of the motor 30 by the vacuum in the system and in the tank 44, and the cut out 57 is provided for cutting out the vacuum switch. By the use of this vacuum controlled switch the pump may be automatically controlled during the daytime 90 or during the time that the system is in full operation, but at night time or whenever it is desired, the switch 57 may be opened so that the motor will not be controlled by the vacuum in the system.

When the manually controlled switch 57 is closed and the vacuum in the system and in the tank 44 falls to a predetermined point, the vacuum controlled switch 47 will close the circuit to the "across the line magnetic switch" 49 which in turn connects the current direct to the motor through the medium of the conductors 50 and 51 and this will start the motor. When the vacuum in the system and tank 44, has reached a predetermined point it will actuate the switch 47 so that it will break the circuit by again causing the operation of the magnetic switch 49, to stop the motor.

When the pump is first started suction 110 will be created by the rotor and will continue until a predetermined vacuum has been created in the system, which will also be manifested in the vacuum tank 44, and as before stated when the vacuum increases beyond a predetermined degree the motor will 115 be stopped through the medium of the vacuum controlled switch 47. When the vacuum drops below a predetermined degree the vacuum controlled switch 47 will again 120 operate to start the motor 30.

If liquid accumulates in the system and the vacuum remains high the liquid will be forced through the pipe 45 due to its head 125 and into the tank 44, the tank 44 will then be water sealed against the vacuum in the system. As the liquid rises in the tank 44 the vacuum therein will drop, causing the switch 47 to cut in and energize the switch 49 to start the pumping operation. This 130

method of operation gives a water line control regardless of the height of vacuum in the system.

If desired the connection 48 leading from the vacuum controlled switch 47 may have communication directly with the pipe 17 and in this event the tank 44 may be eliminated. This arrangement, however, will cause a more frequent actuation of the control device.

If it is desired to operate this device only as a condensation pump and receiver, that is, as for instance at night, or whenever it is desired to keep the system free from water 15 of condensation without maintaining a vacuum on the system, there may be provided means for controlling the operation of the pump by means of the height of the liquid in the system.

20 To that end there may be provided a float 60 located within the tank 10 and which float is connected with a rock shaft 61 journaled in suitable bearings and extending to the outside of the tank 10. Connected with the 25 shaft 61 is an arm 62 which in turn is connected preferably through the medium of a link 63 with an arm or control lever 64 of a switch diagrammatically illustrated as at 65 and which switch 65 may be of the ordinary 30 and well-known construction which operates when the lever 64 is moved in one direction to open the switch and when moved in the opposite direction closes the switch, the operation of the lever 64 being controlled by 35 the rise and fall of the float 60 in the tank 10 under the influence of the amount of liquid in the tank 10. The conductor 56 is connected to one side of the switch 65 and to the other side of the switch 65 is connected a conductor 66 which also has connection with the 40 magnetic switch 49.

When water in the system reaches sufficient head to cause it to flow through the rotor into the casing of the pump and tank 10, the float 45 will rise causing the switch 65 to complete the circuit and energize the magnetic switch 49, which in turn cuts in the motor 30 to the line circuit. This will start the pump and water will be taken from the tank 10 and 50 discharged through the outlet 38 in the manner as hereinbefore described. When the water in the tank 10 falls to a predetermined level, the float 60 will drop and this will operate the switch 65 to de-energize the magnetic switch 49 and stop the motor.

If desired the switch 65 may be actuated through the medium of a float arranged within the tank 44.

60 While the device so operated starts as an ordinary condensation pump does, it has the distinct advantage that it will continue running so long as any water remains in the return line or mains and will completely clear them from water even though the returns are 65 below the level of the pump. The reason for

this is that the rotor will deliver liquid into the pump casing faster than the centrifugal pump can return it to the boiler or feed water heater, thus keeping the float 60 in raised position until water is removed from the system.

The vacuum controlled switch 47 may be operated in conjunction with the switch 65 or may be cut out so that the system will be controlled only by the switch 65 as at night 75 and in order to accomplish this result it is only necessary to open the switch or cut out 57 to interrupt the circuit to the switch 47. In this event the apparatus will operate as a condensation pump and receiver.

80 Should pressure in the boiler or feed water heater rise above the pressure the centrifugal pump is designed to operate against, the water level in tank 10 will rise causing float 60 to rise and operate to close valve 67. Then water or air delivered into tank 10 by rotor 22 will cause pressure in tank 10 enabling the centrifugal pump to operate against a higher pressure, in other words it double stages the pump.

85 This float controlled valve 67 has another function as it will at all times prevent water being lost through vent 11, thus retaining all water in system.

The switches 65 and 47 are preferably of the ordinary single or double pole type.

90 It is thought that the operation of the device will be clearly understood from the foregoing, but briefly stated it is as follows.

95 When used as an ordinary condensation pump and receiver the switch or cut out 57 is opened, rendering inactive the vacuum controlled switch 47, and assuming that the motor 30 is idle, the water of condensation in the system will then accumulate and will flow 100 through the rotor into the tank 10 and accumulate therein until the liquid level in the tank 10 rises sufficiently to raise the float 60, this will actuate the switch 65 to complete the circuit through the motor 30, starting the 105 latter and operating the rotor 22 and centrifugal pump 36. The water of condensation is drawn from the system by the suction of the rotor, and the centrifugal pump 36 is supplied with water from the tank 10, the 110 water from the centrifugal pump being delivered through the passage 14 and discharge opening 38 back to the boiler or feed water heater. This operation will continue until the liquid level in the tank 10 lowers sufficiently to permit the float 60 to drop a sufficient distance to again operate the switch 65 to cut out the motor 30. The same operation will be repeated from time to time as the liquid level in the tank rises and falls.

115 When, however, it is desired to control the operation of the apparatus by the vacuum, the cut out 57 will be closed and when the apparatus is running, the predetermined degree of vacuum in the system will be mani- 120 125 130

fested in the vacuum tank 44. If the vacuum in the system increases the vacuum controlled switch 47 will operate to stop the pump and if the vacuum falls below the predetermined 5 degree the vacuum in the tank will operate to control the switch 47 to again start the pump. If water accumulates in the system and the vacuum remains high, the tank 44 will be water sealed against the vacuum in 10 the system. The head of water when sufficiently high will cause the water to enter the tank at which time the vacuum in the tank will decrease rapidly causing the switch 47 to cut in and energize the motor to start 15 the pump operating, thus giving a water line control regardless of the height of vacuum in the system.

With the present construction it will be noted that the air, vapors, and water which 20 are discharged into the tank or receiver 10, are delivered thereinto above the normal liquid level in the receiver, with the result that less power is required than would be necessary in the event that the air, vapors 25 and water are delivered into the receiver below the normal liquid level therein.

The initial supply of water for the tank or receiver 10 may be delivered thereto as by city pressure through a suitably controlled 30 opening 68. This opening may also be employed, when desired, as a clean out opening for the tank or receiver.

While the preferred form of the invention has been herein shown and described, it is to 35 be understood that various changes may be made in the details of construction and in the combination and arrangement of the several parts, within the scope of the claims, 40 without departing from the spirit of this invention.

What is claimed as new is:—

1. An apparatus of the character described including a separating receiver normally open to the atmosphere, a hydro-turbine 45 pump within the receiver for withdrawing gases, vapors and water of condensation from a heating system and delivering the same into the receiver, means for supplying liquid to the pump from a point in proximity to the bottom of the receiver, and a centrifugal pump exterior of the receiver and having communication therewith for withdrawing water from the receiver and delivering the same to a boiler or the like. 50

55 2. An apparatus of the character described including a separating receiver normally open to the atmosphere, a hydro-turbine pump within the receiver for withdrawing gases, vapors and water of condensation from a heating system and delivering the same into the receiver, means for supplying liquid to the pump from a low elevation in the receiver, a centrifugal pump for withdrawing water from the receiver and deliv- 60

ering the same to a boiler or the like, and a valve mechanism controlled by the height of the liquid in the receiver for closing the receiver to the atmosphere, whereby the first recited pump will cause an increased pressure to be exerted upon the liquid in the receiver supplied to the second recited pump. 70

3. An apparatus of the character described including a separating receiver, a hydro-turbine pump for withdrawing gases, vapor and water from a heating system and delivering them into the receiver, said pump embodying a casing, said casing being disposed within and forming an integral structure with the said receiver, an inlet to the casing leading to a point in proximity to the bottom of the receiver whereby liquid will be delivered from a low elevation in the receiver to the pump, a centrifugal pump for withdrawing liquid from the receiver and delivering the same to a boiler or the like, and means for operating the pumps. 80

4. An apparatus of the character described including a separating receiver, a hydro-turbine pump for withdrawing gases, vapor and water from a heating system and delivering them into the receiver, said pump embodying a casing, said casing being disposed within and forming an integral structure with the said receiver, an inlet to the casing leading to a point in proximity to the bottom of the receiver whereby liquid will be delivered from a low elevation in the receiver to the pump, a centrifugal pump for withdrawing liquid from the receiver and delivering the same to a boiler or the like, means for operating the pumps, and means for causing said pumps to operate as a two stage pump. 90

5. An apparatus of the character described including a separating receiver, a hydro-turbine pump for withdrawing gases, vapor and water from a heating system and delivering them into the receiver, said pump embodying a casing, said casing being disposed within and forming an integral structure with the said receiver, an inlet to the casing leading to a point in proximity to the bottom of the receiver whereby liquid will be delivered from a low elevation in the receiver to the pump, a centrifugal pump for withdrawing liquid from the receiver and delivering the same to a boiler or the like, means for operating the pumps, said receiver being normally open to atmosphere, and a valve controlled by the height of the liquid in the receiver for closing the receiver to the atmosphere, whereby the first recited pump will cause an increased pressure to be exerted upon the liquid in the receiver supplied to the second recited pump. 100

In testimony whereof I have signed my name to this specification, on this 25th day of April, A. D. 1924.

BENJAMIN SKIDMORE, JR.
